(No Model.)

R. WORSLEY.
WINDMILL.

No. 408,946.

Patented Aug. 13, 1889.

UNITED STATES PATENT OFFICE.

ROLLIN WORSLEY, OF NEWARK, ILLINOIS.

WINDMILL.

SPECIFICATION forming part of Letters Patent No. 408,946, dated August 13, 1889.

Application filed November 12, 1888. Serial No. 290,549. (No model.)

To all whom it may concern:

Be it known that I, ROLLIN WORSLEY, of Newark, in the county of Kendall and State of Illinois, have invented a new and Improved

5 Windmill, of which the following is a full, clear, and exact description.

The invention relates to an improvement in the means for supporting the jointed horizontal shaft which carries the wheel proper and 10 transmits rotation to the vertical or tower shaft, from which the power is taken for any desired purpose.

Reference is to be had to the accompanying drawings, forming a part of this specification, 15 in which similar letters of reference indicate corresponding parts in both the figures.

Figure 1 is a plan view of the improvement, and Fig. 2 is a side elevation of the same.

In a windmill-frame as formerly constructed, 20 with a solid frame and beveled gears to connect the horizontal and perpendicular shafting, it has been found that when a strain was applied to the driven shaft for the purpose of driving machines, or for work of any kind, the 25 gear-wheel on the driving-shaft revolves around a pinion on the driven shaft and carries the wind-wheel frame with it, unless held to its place by some device which counteracts the revolving motion of the wind-wheel frame.

30 In some windmills rudders set at an angle have been used, or side or top vanes have been employed, or combinations of gears and worm-wheels have been utilized, to hold the frame in position with the wind-wheel square- 35 ly facing the wind. If the wind-wheel is allowed to turn edgewise to the wind, it naturally loses a large part of its power for work.

In my invention, presently to be described, the above-named serious defect is entirely 40 avoided.

In the tower A, of any approved construction, is mounted to turn in suitable bearings the vertical shaft B, carrying on its upper end a bevel-pinion C, meshing into a bevel gear- 45 wheel D, secured on the shaft E, connected by a universal joint F with the wind-wheel shaft G, carrying on its outer end the wind-wheel H. The shafts E and G are mounted to turn in the wind-wheel frame I, made in two parts 50 J and K, hinged together at L, located in

line with the center of the universal joint F. The frame part J is mounted to turn loosely in bearings in the top of the tower, as is plainly illustrated in Fig. 2.

The operation is as follows: The wind, acting 55 on the face of the wind-wheel H, rotates the latter, so that the shaft G is turned, and turns, by the universal joint F, the shaft E, which, by the gear-wheels D and C, transmits the rotary motion of the wheel to the shaft B, 60 connected in the usual manner with the machinery to be driven. Now, the purpose of having the wheel-frame I and the wind-wheel shaft made flexible at the point between the tower-pivot and the wind-wheel is to prevent 65 the wind-wheel from being drawn partly out of the direct line of the wind by the bevel-gears D and C pulling the wind-wheel H around the pivot on the shaft B.

It is understood that the tendency of the 70 wind-wheel H to pull out of the wind by the resistance of work applied to driven shaft B is overcome by allowing the frame part J to swing on its tower-pivot, as shown in dotted lines in Fig. 1, while the other frame-section 75 K moves parallel with its former position, thus keeping the wind-wheel H directly in the face of the wind. It is understood that the universal joint F and the pivots L permit such a movement. The frame part J acts as 80 a lever to draw the gear-wheels D and C back to their place, and whenever the strain on the gear and frame is equal to the pressure of the wind against the wind-wheel then the frame will remain stationary and the wheel will 85 revolve with its face squarely to the wind, thereby exerting its greatest power.

The invention applies more particularly to the style of windmills called "vaneless"—that is, it runs back of the tower or pivot and requires no vane or rudder to hold its face to the wind. The distance that the main frame part J moves out of the line depends on the distance from the tower pivot-shaft B to the hinge L, and also the proportionate sizes of 95 the wheels D and C used and the power of the wind-wheel H.

Having thus fully described my invention, I claim as new and desire to secure by Letters Patent—

1. In a windmill, the combination, with a wind-wheel frame mounted to turn and made in two parts hinged together, of a wind-wheel shaft mounted to turn in the said wind-wheel frame, and also made in two parts universally jointed together in line with the frame-joint, substantially as shown and described.
2. In a windmill, the combination, with a wind-wheel, of a wind-wheel shaft mounted to turn and made in two parts universally jointed

together, a wind-wheel frame mounted to swing and made in two parts hinged together in line with the universal joint, and means, substantially as described, for transmitting 15 the rotary motion of the wind-wheel shaft to the power-shaft, as set forth.

ROLLIN WORSLEY.
